SMOKING APPARATUS

George F. Heubeck, Baltimore, Md.

Application June 3, 1935, Serial No. 24,740

1 Claim. (Cl. 131—12)

This invention relates to improvements in smoking apparatus; and more particularly, pipe, cigar and cigarette holders wherein a dry cool smoke is obtained by causing the smoke to travel over an extended surface intermediate the source of smoke and the mouth piece. Many efforts have been made to accomplish this result by air vents, metal tube inserts, pads and wells for the collection of saliva, but few, if any, have been successful as in most cases the obstruction becomes clogged and soon passes its period of usefulness.

The principal object of my invention resides in providing a large cylinder surface over which the smoke must pass, thus giving it a chance to cool and lose the moisture present therein.

Another object is to provide tortuous passageways formed on the exterior of the cylinder, said cylinder containing receptacles for the collection of moisture.

Still another object is to provide a simplified structure which is easily taken apart for cleaning.

Other objects will be disclosed in the specification and drawing forming a part of this application.

In the drawing:

Figure 1 is a vertical section of a smoking pipe;

Figure 2 is a section taken on line 2—2 of Figure 1;

Figure 3 is a section taken on line 3—3 of Figure 2;

Figure 4 is a detailed perspective of the cylinder removed from the smoke receptacle; and

Figure 5 is a modification adapted to be used as a cigar holder.

Referring to the drawing in which similar parts are designated by like numerals:

Numeral 6 designates a pipe having a bowl 7 with an upwardly slanting passage 8 connecting with a smoke chamber 9. Within the smoke chamber 9 is placed a shell 10 having an opening 10' in alignment with the passage 8. Threaded into the shell 10 is a cylinder 11 having baffles 12 and channels 13. A passage 14 connects with the inner surface 15 of the hollow cylinder 11. A discharge exit 16 formed in one of the channels 13 connects with a passage 17 in stem 18. One end 19 of the stem 18 fits into a housing 20 formed integral with the cylinder 11. Between the wall 21 of the housing 20 and the end 19 of the stem is formed a pocket 22 to collect moisture.

Within the hollow cylinder 11 may be placed absorbent cotton 23 (or similar material) impregnated with menthol, oil of peppermint, or similar ingredients, to serve as a strainer for the smoke and permit the smoker to inhale the ingredients placed on the cotton.

As actually used, the smoke will be drawn from

the bowl 7 through the passage 8 into the chamber 9 through the opening 10' in the shell 10, through the cotton 23, if the same be used, and in turn through the passage 14 into the channel 13. The shell 10 fits snugly around the cylinder 11 and contacts with the baffles 12 so that the smoke must pass from the channels 13 containing the exit 16, the smoke pursuing a weaving course through the various channels and around the baffles until it has completed the circuit of the cylinder, passing out through the discharge exit 16 into the pocket 22 and in turn through the stem 18 to the smoker's mouth. The weaving course of the smoke affords an opportunity for the smoke to cool, deposit moisture in the channels, and come to the mouth of the smoker devoid of many of the objections present in pipe smoking.

My pipe may be quickly taken apart, cleaned and reassembled without difficulty, and presents exposed surfaces which may be readily cleaned.

Figure 5 shows a modified form of my invention comprising the same structure, except that a cigar holder is substituted for the pipe bowl. It is also understood that this can likewise be used as a cigarette holder with slight modifications.

Numerous variations may doubtless be devised by persons skilled in the art without departing from the principles of my invention. I, therefore, desire no limitations to be imposed on my invention, except such as are indicated in the appended claim.

What I claim is:

A smoking device comprising a member provided with a tobacco receiving recess and with a smoke receiving chamber, a shell slidable with friction fit in said chamber, and having an opening in the end thereof adjacent said recess, said member having a passageway sloping upwardly from said recess into communication with the opening in said shell, a smoke cooling structure fitting slidably and rotatably with friction fit in said shell, said structure being provided on its outer surfaces with a series of connecting channels separated by baffles, said channels being provided with elongated baffles spaced from the walls of the channels and forming spreaders to cause the smoke to pass around the opposite sides of the spreaders, one end of said series of channels having a passageway connected with said smoke chamber and the other end having a smoke exit, and a mouthpiece detachably secured to said structure, and having a bore therethrough parallel to the axis of said shell and structure and displaced upwardly with respect to said axis, said smoke exit being formed as a passageway downwardly directed from the upper part of said structure to the bore of said mouthpiece.

GEORGE F. HEUBECK.
